STANLEY W. NICHOLSON, OF TOLEDO, OHIO, ASSIGNOR TO DURA MECHANICAL HARDWARE COMPANY, OF TOLEDO, OHIO, A CORPORATION OF DELAWARE.

WINDOW-CONTROLLING MECHANISM.

1,412,569.

Specification of Letters Patent. Patented Apr. 11, 1922.

Application filed July 10, 1920. Serial No. 395,314.

To all whom it may concern:

Be it known that I, STANLEY W. NICHOLSON, a citizen of the United States of America, residing at Toledo, in the county of

5 Lucas and State of Ohio, have invented certain new and useful Improvements in Window-Controlling Mechanism, of which the following is a specification, reference being had therein to the accompanying drawings.

10 This invention relates to vehicle window control mechanisms and more particularly to control mechanisms for automobile windows.

15 It is the object of the invention to provide a spring actuated counterbalancing arm arranged beneath a vertically slidable window member and acting upwardly thereupon, and to associate with said arm actuating means therefor and a locking mechanism under 20 control of said actuating means.

The invention consists in the structural features and arrangement of parts herein-after fully described and illustrated in the accompanying drawing, wherein:

25 Figure 1 is an interior view of a motor vehicle door equipped with a sliding window member to which the present invention is applied;

30 Figure 2 is an enlarged view of the combined counterbalancing and locking mechanism as seen in Figure 1, the locking mechanism being shown in locked position;

Figure 3 is a top view of the same;

35 Figure 4 is a sectional view taken upon line 4-4 of Figure 3 and showing certain elements of the locking mechanism which are concealed in Figure 2;

40 Figure 5 is a fragmentary view similar to Figure 4, but showing the unlocked position of the locking mechanism, which position results from upward actuation of the actuating member.

45 In these views the reference character A designates an automobile door having its lower portion chambered as indicated at A' and having its upper portion formed with a window opening B having a transparent closure C, which is vertically slidable and which enters the chamber A' upon being lowered. The window member C is counterbalanced by a mechanism located in said chamber A' and comprising an arm D having at one end a roller E adapted to bear upon the lower edge of the window member

55 C, while its other extremity is pivoted upon a stub shaft F and is engaged between two bracket members G and G' in which said stub shaft is mounted. Said arm is spring counterbalanced, the counterbalancing effort being exerted preferably by a plurality of 60 springs H' arranged within a slot H² of said arm and anchored at their outer ends at the various points H³, transversely spaced upon the arm, while the inner ends are connected through a common anchorage member to a 65 pin H⁴ carried by one of the bracket members G, G' at a point above the stub shaft F. Normally the arm D is locked against pivotal movement and consequently the window member C is normally locked against sliding 70 movement (since the free extremity of said arm engages the lower edge of said window member). To effect the desired locking, the pivotal end of the arm D is rounded about the stub shaft F and is notched to form a 75 toothed quadrant, as indicated at H. This quadrant is normally engaged by a pair of opposed detents I pivoted between the bracket members G, G', and maintained normally oppositely engaged with the quadrant 80 H by a common leaf spring J. In order to effect a clockwise swinging of the arm D so as to actuate the window member downwardly, the upper detent I must first be disengaged from the quadrant H and disengagement of the lower detent I is a prerequisite to counter clockwise swinging of the arm D, such as effects the raising of the window member.

85 As a common control means for the described locking mechanism and actuating means for the arm D, there is provided a handle member K adjacent the inner face of the door A, said handle member having a hub portion K', which extends into the 90 chamber A' and through which bolts L are passed, rigidly securing said handle member to an arm M within the chamber A'. The end of said arm to which the hub K' is bolted is formed with a transverse slot M', 100 which engages an enlarged portion N of the stub shaft F, the other end of said arm being pivoted upon a pin O carried by the arm D at one side of the axis of said arm. Preferably the handle member K is substantially 105 parallel to the axis of the arm D and consequently occupies an acute angular relation to the arm M, this relation being best indi-

cated in Figure 2. P is a trip plate for alternatively releasing the detents I from the quadrant H upon actuation of the handle member K, said plate being pivoted at P' upon one of the bracket members G, G' at a point intermediate the two detents, and having shoulders P² at opposite sides of its pivot for engagement with pins R respectively projecting from the detents I through 10 slots S formed in the bracket member G'. Said trip plate is furthermore formed with a pair of prongs T, which engage at each side of the circular end portion T' of the arm M, in which portion the slot M' is formed. Normally the trip plate P is maintained in the substantially horizontal position indicated in Figure 2, in which position the shoulders P² are vertical and permit engagement of the detents I with the 15 quadrant H. This normal position of the trip plate is maintained by a coiled spring U, which is arranged vertically in a slot U', centrally formed in the plate between the prongs T, tongues U² being bent at a right angle to the trip plate to form abutments for said spring. Furthermore, said spring abuts against tongues U³, struck out from the bracket member G' and having sufficient clearance from the prongs T to permit rocking 20 of the trip plate P between its limiting positions, one of which is shown in full lines in Figure 5.

In the operation of the described invention, the spring U' abutting jointly against 35 the tongues U² and U³ formed respectively upon the trip plate P and bracket member G', holds the trip plate in its horizontal position shown in Figure 2, in which position both detents I engage the quadrant H and 40 lock the arm D against swinging either upwardly or downwardly. To swing said arm downwardly, the handle K is actuated in a downward direction and the first result is an upward swinging of the arm M about 45 the pivot O, so as to shift said arm to the position indicated in Figure 5. Owing to the prongs T of the trip plate embracing the circular extremity T' of the arm M, said trip plate is rocked as shown in Figure 5, as the 50 result of said pivotal movement of the arm M, and consequently the upper shoulder P² of the trip plate exerts a thrust upon the pin R of the upper detent to disengage said detent from the quadrant, as is clearly seen in 55 Figure 5. Thereupon, the arm D will respond by clockwise swinging to the effort exerted upon the handle member K, and the window member C will be lowered. Correspondingly when an upward stress is exerted 60 upon the handle member K, the arm M is first swung downwardly about its pivot O within the limits established by the slot M', thus acting upon the lowermost prong T of the trip plate to rock the latter downwardly 65 and shift the lower detent S out of engage-

ment with the quadrant, and continued upward pressure upon the handle member K will swing the arm D in a counter-clockwise direction and effect raising of the window member C. Upon release of the handle member K, the spring U will return the trip plate P, the arm M and the handle K to their normal positions and the two detents will again resist swinging of the arm D in either direction. In the limiting lowermost 70 position of the window member C an isolated tooth W on the quadrant D engages the lowermost detent I and resists the action of the springs H' on arm D, which action is in said position at a maximum. 75

It is a feature of the described construction that the counterbalancing arm and springs, together with the actuating handle and locking mechanism, constitute a unit, said parts being mounted upon the brackets G and G'. 80

What I claim as my invention is:

1. In a vehicle window control mechanism the combination with a vertically sliding window member, of a pivotal control element for said member, a detent having latch engagement with the pivotal end of said element, a tripping member for said detent pivoted eccentrically to said actuating element and an actuating member for said control element acting upon initial actuation upon the tripping member to release the control element from said detent. 95

2. In a vehicle window control mechanism the combination with a vertically slidable 100 window member, of a pivotal control element for said member, a pair of oppositely arranged detents respectively opposing turning of the control element in opposite directions, a trip plate pivoted intermediate 105 said detents for alternatively releasing the same from said control element, and a common actuating member for said control element and for said tripping plate acting initially upon the latter and upon the former after release of the same through actuation of said tripping plate. 110

3. In a vehicle window control mechanism the combination with a vertically slidable window member, of a pivotal control element for said member, a quadrant carried by said element concentric with the pivot thereof, a pair of detents oppositely engaging said quadrant, a common means for alternatively tripping said detents, and means 115 actuatable to initially trip one of said detents and to subsequently actuate the control element counter to said detent. 120

4. A vehicle window control mechanism comprising a vertically slidable window member, a pivotal control element for said member, a quadrant carried by said control element concentric with the pivot thereof, a pair of opposed detents engageable with 125 said quadrant, a common means maintain- 130

- ing said detents normally in engagement with the quadrant, a tripping member pivoted intermediate said detents, and an actuating member for said tripping member and 5 control element acting initially to rock the tripping member to retract one of the detents according to the direction of actuation of the actuating member, and subsequently acting to turn the control element.
- 10 5. In a vehicle window control mechanism the combination with a vertically sliding window member, of a pivotal control element for said member, a quadrant carried by said arm concentric with the pivot there- 15 of, a pair of detents oppositely engageable with said quadrant to normally lock the control element against turning means normally engaging said detents with said quadrant, a pivotal tripping member having 20 portions for alternative engagement with said detents to release the same according to the direction which said tripping member is rocked, and provided with opposed prongs, an actuating member for said control element and a connection between said actuating member and control element having 25 a portion engaged between the prongs of the tripping member and adapted for a limited movement against said prongs 30 whereby upon actuation of the actuating member, an initial rocking of the tripping member is effected and a subsequent turning of the control element.
6. In a vehicle window control mechanism 35 the combination with a vertically sliding window member, of a pivotal control element for said window member, a quadrant carried by said control element concentric with its pivot, a pair of detents oppositely 40 engaging said quadrant, a tripping member alternatively engageable with said detents and normally occupying a neutral position, means maintaining both of said detents engaged with the quadrant in said neutral 45 position of the tripping member, a spring acting on the tripping member to normally maintain said neutral position, and actuating means for the control element initially 50 acting upon said tripping member to rock the same from its neutral position according to the direction of actuation to disengage the proper detent to permit subsequent turning of the control element through such actuation.
- 55 7. In a window control mechanism, a vertically slidable window member, a pivotal control element for said window member, latch means for said control element, an actuating member for said control element, and a member pivoted upon said control element eccentrically as regards the pivotal axis thereof, forming a lost motion drive connection from the actuating member to said control ele- 60 ment, and acting in the taking up of its lost motion to release said latch means. 65
8. In a window control mechanism, a vertically slidable window member, a pivotal control element for said window member, latch means for said control element, an actuating member for said control element, and a member pivoted upon said control element forming a lost motion driving connection from said actuating member to said element and engaged with the pivot of said element to limit its lost motion movement, said member acting through its lost motion movement upon said latch means to release the control element from said means. 70
9. In a vehicle window control mechanism, the combination with a vertically slidable window member, of a pair of oppositely arranged detents respectively opposing raising and lowering of said window member, a trip plate pivoted intermediate said detents for alternatively releasing the same, and a common actuating means for said window member and for said tripping plate acting initially upon the latter and shifting the former after release of the same through actuation of said tripping plate. 75
10. In a vehicle window control mechanism, comprising a vertically slidable window member, a pair of opposed detents respectively normally resisting actuation of said window member upwardly and downwardly, a common means yieldably maintaining said detents in their normal positions, a tripping member pivoted intermediate said detents, and actuating means for said tripping member and sliding window 80 member acting initially to rock the tripping member to thereby retract one of the detents according to the direction of actuation of the actuating member and subsequently shifting the window member. 90
11. In a vehicle window control mechanism, the combination with a vertically slidable window member, of a pair of detents respectively opposing actuation of said window member upwardly and downwardly, a tripping member alternatively engageable with said detents and normally occupying a neutral position, means maintaining the effective positions of said detents in the neutral position of the tripping member, a 85 spring acting on the tripping member to normally maintain its neutral position, and actuating means for the sliding window member initially acting upon said tripping member to rock the same from its neutral position 95 according to the direction of actuation to disengage the proper detent to permit the desired actuation of the window member. 100
